UNITED STATES PATENT OFFICE

2,487,935

RIGHT-ANGLE UNDERCUTTER

Jesse W. McClendon, Tampa, Fla.

Application September 5, 1947, Serial No. 772,352

4-Claims. (Cl. 90—12)

1

The present invention relates to undercutting machines and it consists in the combinations, constructions and arrangements of parts herein described and claimed.

It is an object of the present invention to provide a machine for undercutting the insulation between the segments of the commutators of motors and generators.

A further object of the invention is the provision of means, in a machine of this character, for providing for undercutting in a vertical or horizontal direction at the will of the operator and with a minimum of time needed for changing from one type of undercutting to the other.

Another object of the invention is the provision of novel means and mechanisms for the mounting of a motor or generator armature in the machine.

Another object of the invention is the provision of novel means and mechanism for adjusting and limiting the linear movement of a saw utilized in the invention.

Other and further objects of the invention will become apparent from a reading of the following specification taken in conjunction with the drawing, in which:

Figure 1 is a plan view of an embodiment of the invention.

Figure 2 is a side elevational view thereof.

Figure 3 is a front elevational view of the invention.

Figure 4 is a sectional view taken along line 4—4 of Figure 2.

Figure 5 is a fragmentary side elevational view taken from the opposite side to that shown in Figure 2.

Figure 6 is an enlarged fragmentary sectional view taken substantially along line 6—6 of Figure 3, and

Figure 7 is a perspective view of an element of the invention.

It is well-known that the commutator segments in the armatures of generator and starter motors for automobiles as at present constructed invariably lie parallel to the armature shaft while in other fields such as refrigeration and the like the commutator segments lie in a plane at right angles to the axis of the commutator shaft.

The present invention comprises a machine adapted to undercut the insulation, usually mica, beneath such segments and to be quickly and easily adapted to change from the undercutting of one type of commutator to another.

Referring then for a more complete understanding of the invention to the drawings, there

2

is shown, therein, an undercutting machine having a base 10 of hollow construction adjacent the front end of which is affixed a vertically extending support 11 in which is slidably mounted a cylindrical column 12 to the upper end of which is affixed a horizontal supporting member 13 in the forward end of which is affixed a guide tubing 14 having a collar 15 at its upper end upon which rests the hub 16 of a handle 17.

Dependant from the hub 16 and extending through the tubing 14 is a rod 18. The upper end of the support 11 is provided with a forwardly extending integrally formed dog 19 through which the tubing 14 is adapted to pass.

An anchoring dog 20 is also formed in the support 11 below the dog 19 and serves as an anchoring base for a nut plate 21 having a dependant collar 21a through which the rod 18 is threaded and which is provided with a slot 22 at either side in

which may be engaged thumb nuts 23 carried by bolts 24 pivoted, as indicated at 25, to the anchoring dog 20. When the rod 18 is in lowered position, it depends into the base through a smooth opening in the latter.

In the rear end of the supporting member 13 is removably mounted, by means of a pair of set screws 26, a cutter head assembly 27.

Adjacent the rear end of the base 10 is provided a transversely extending support 28 to one end of which is pivotally mounted, as indicated at 29, an arm 30, to which is affixed a forwardly extending lever 31 having a handle 32 and interconnected with the supporting member 13 by a link 33.

Referring to Figure 6 particularly, it will be seen that the cutter head assembly 27 comprises a housing 34 in which is mounted a spindle shaft 35 by means of bearings 36 and 37. The shaft is provided with a head 38 in which is removably mounted by means of a set screw 39 a mandrel 40 which may, of course, be changed as desired to one of lesser or greater length. At the outer end of the mandrel is mounted a saw 41 by means of a screw 42. The shaft 35 has adjustably mounted thereon a pulley 43 by means of a set screw 44 and a collar 45 is interposed between the bearing 36 and pulley 43 and is provided with a pair of diametrically opposed laterally extending compression springs 46 adapted to bear against the pulley 43 to take up play whenever end drift may occur in the assembly and before the same is taken up by resetting the position of the pulley 43 by means of the set screw 44.

An electric motor 47 is mounted upon a platform 48 affixed to the rear end of the base by

screws 49 or the like and is provided with a pulley 50. A suitable switch 51 is provided in the forward end of the base 10 for controlling the operation of the motor 47.

Adjacent the support 28 is affixed to the base 10 a supporting member 52 in which is pivoted, as indicated at 53, a forwardly extending arm 54, the outer end of which carries an idler pulley 55. A belt 56 is trained over the pulleys 43, 50 and 55.

A pair of longitudinally extending carriage rods 57 and 58 have their ends mounted in the supports 11 and 28 and slidably mounted upon the rods 57 and 58 is a carriage 59 in which is pivotally and slidably mounted a cylindrical longitudinally extending column 60 to the forward end of which is affixed an upwardly extending arm 61. A like arm 62 is affixed to a collar 63 which is slidably engaged upon the column 60 and is provided with an opening for the reception of a guide rod 64 affixed in parallel relation to the column 60 in a dependant dog 65 carried at the rearward end of the column 60.

The axial position of the arm 61 may be varied by means of a hand screw 66 mounted in the carriage 59 and adapted to lock the column 60 in selected positions and a like screw 67 is also provided for locking the carriage 59 with respect to the rod 57.

The upper end of the rod 61 is provided with a seat 68 having a stem 69 adjustably mounted therein by means of a screw 70. The arm 62 has slidably mounted in its upper end a rod 71, the rearward end of which carries an operating handle 72 and the forward end of which has affixed thereto a seat 73. A compression spring 74 is interposed between the seat 73 and the arm 62.

An adjustable stop member 75 is slidably mounted upon the rod 57 between the carriage 59 and support 11 and is provided with a hand screw 76 for locking the same in selected positions.

A dependant bracket 77 mounted in the hollow base 10 has journaled therein a shaft 78 which protrudes through the side of the base 10 and carries on its outer end a lever 79 having a handle 80. The inner end of the shaft 78 has affixed to it by means of a screw 81, an arm 82 which extends upwardly through a slot 83 in base and has its upper end interconnected with the carriage 59 by means of a link 84.

In operation, it will be apparent that to undercut a commutator having longitudinally extending segments as, for example, that shown in Figures 1 and 2, at 85, the shaft of the armature will be placed in the seats 68 and 73 and the carriage 59 will then be brought forwardly by means of the lever 79 until the commutator registers with the saw 41. The rod 18 is then turned by means of the handle 17 to move the cutter head assembly 27 downwardly until the saw almost touches the commutator. The armature is then revolved until insulation is directly beneath the saw. The motor 47 is then started by means of the switch 51. The handle 17 is then turned until the saw cuts into the insulation a sufficient depth, usually .025. The lever 79 is then utilized to bring the carriage 59 forwardly until the cut in the insulation has been extended as far back on the commutator as is desired. The stop 75 is then locked in position upon the rod 57 adjacent the carriage 59 by means of the hand screw 76. The lever 79 is then reversed until the commutator is clear of the saw, thereby completing the

first circuit. The armature is then revolved until the next insulation is in line with the saw and the lever 79 is now worked backwardly and forwardly to complete a second circuit. This operation is continued until all of the insulations are cut.

To undercut a commutator having its segments aligned at right angles to the axis of its shaft, as shown in Figure 5, for example, the shaft is placed upon the seats 68 and 73 and the carriage 59 is brought forward by means of the lever 79 until the commutator 86 almost touches the saw 41. The armature is then revolved until insulation is directly in line with the saw. The motor 47 is then started by means of the switch 51 and the carriage 59 brought forward with the lever 79 until the saw cuts to a sufficient depth. The carriage 59 is then locked by means of the hand screw 67 on the carriage rods 57 and 58. The handle 17 is then revolved until the cutter head assembly 27 is moved downwardly as far as desired. This is usually to the conventional annular groove adjacent the armature shaft. The nut plate 21 is then released from the anchoring dog 20 by loosening the nuts 23 upon the bolts 24 and revolving the bolts to a hanging position. The lever 31 is then moved upwardly until the saw 41 closes the outer periphery of the commutator thereby completing the first cut. The armature is then revolved until the next insulation is in line with the saw 41. The lever 31 is then depressed until the anchor plate 21 comes into contact with the anchoring dog 20 which forms a positive stop for such downward cut of the saw. The lever 31 is then again brought up to clear the upper end of the commutator, thereby completing the second cut. Repeating the last operation after revolving the commutator to the successful insulation points is then in order to complete the job of removing the insulation from between the commutator segments.

While but one form of the invention has been shown and described herein, it will be readily apparent to those skilled in the art that many minor modifications may be made without departing from the spirit of the invention or the scope of the appended claims.

What is claimed is:

1. A device of the character described comprising a motor-operated saw, a carriage, means on said carriage for holding a work piece thereon, means for reciprocating the carriage and said work piece horizontally, means for adjusting and limiting said movement, means for reciprocating the saw vertically and means for adjusting and limiting said last-mentioned movement said means for reciprocating the saw vertically including a cutter assembly for the saw, a support for said cutter assembly, a base for the entire mechanism, a vertical supporting member on said base, a cylindrical column vertically dependant from the support for the cutter assembly and slidably mounted in the vertical supporting member, a vertically dependant rod revolvably mounted in the support for the cutter assembly, a handle for turning the rod, a nut plate threaded upon said rod and an anchoring dog mounted upon the vertical supporting member for limiting the downward movement of the nut plate.
2. A device of the character described comprising a motor-operated saw, a carriage, means on said carriage for holding a work piece thereon, means for reciprocating the carriage and said work piece horizontally, means for adjusting and limiting said movement, means for reciprocating

the saw vertically and means for adjusting and limiting said last mentioned movement said means for adjusting and limiting the horizontal movement of the carriage including a pair of rods, the carriage slidably mounted upon said rods, a hand screw threaded into the carriage and adapted to bear against one of the rods and said means for reciprocating the saw vertically including a cutter assembly for the saw, a support for said cutter assembly, a base for the entire mechanism, a vertical supporting member on said base, a cylindrical column vertically dependant from the support for the cutter assembly and slidably mounted in the vertical supporting members, a vertically dependant rod revolvably mounted in the support for the cutter assembly, a handle for turning the rod, a nut plate threaded upon said rod and an anchoring dog mounted upon the vertical supporting member for limiting the downward movement of the nut plate.

3. A device of the character described comprising a motor-operated saw, a carriage, means on said carriage for holding a work piece thereon, means for reciprocating the carriage and said work piece horizontally, means for adjusting and limiting said movement, means for reciprocating the saw vertically and means for adjusting and limiting said last mentioned movement, said means for adjusting and limiting the horizontal movement of the carriage including a pair of rods, the carriage slidably mounted upon said rods, a hand screw threaded into the carriage and adapted to bear against one of the rods and said

means for reciprocating the saw vertically including a cutter assembly for the saw, a support for said cutter assembly, a base for the entire mechanism, a vertical supporting member on said base, a cylindrical column vertically dependant from the support for the cutter assembly and slidably mounted in the vertical supporting members, a vertically dependant rod revolvably mounted in the support for the cutter assembly, a handle for turning the rod, a nut plate threaded upon said rod, an anchoring dog mounted upon the vertical supporting member for limiting the downward movement of the nut plate and means for locking the nut plate upon the anchoring dog.

4. A device as defined in claim 3 wherein the means for locking the nut plate upon the anchoring dog includes a pair of bolts pivotally mounted at opposite sides of the dog, slots formed in the plate and nuts carried by the bolts for engaging the plate when the bolts are turned into the slots.
